Patented Oct. 2, 1956

178,904

WRIST CARRYING SIGNAL LIGHT

Sidney Schwartz, New York, N. Y., assignor to Bantam-Lite, Inc., New York, N. Y., a corporation of New York

Application November 22, 1955, Serial No. 38,986

Term of patent 14 years

(Cl. D72—1)

Fig. 1 is a perspective view showing the top, front and right side of a wrist carrying signal light showing my new design, the wrist band being shown in broken lines.

Fig. 2 is a perspective view showing the bottom, rear and left side thereof.

Fig. 3 is a top plan view thereof.

Fig. 4 is a right side elevational view thereof, and

Fig. 5 is a front elevational view thereof.

The dominant features of my new design are shown in solid lines.

I claim:

The ornamental design for a wrist carrying signal light, as shown and described.
